JOHN LOEFFLER, OF VALLEJO, CALIFORNIA.

SPARK-GAP FOR WIRELESS TELEGRAPHY.

1,117,681.

Specification of Letters Patent. Patented Nov. 17, 1914.

Application filed March 17, 1913. Serial No. 754,754.

To all whom it may concern:

Be it known that I, JOHN LOEFFLER, a citizen of the United States, residing at Vallejo, in the county of Solano and State of California, have invented certain new and useful Improvements in Spark-Gaps for Wireless Telegraphy, of which the following is a specification.

My invention relates to an improved apparatus employed in radio-telegraphy, and more particularly to an improved spark discharge adapted for use in the primary or closed oscillating circuit of a radio-telegraph sending station, and the invention has for its principal object to provide a quenched spark discharge in which the electrodes are capable of fine adjustment to regulate the spark gap so that the apparatus may be properly tuned to obtain the most efficient results; to provide means for maintaining cool the sparking surfaces by conveying the generated heat therefrom and by so doing preventing the sparks formed therebetween from unduly heating the sparking surfaces and causing arcs as the same are discharged from the electrodes, and to provide a structure having a receptacle or chamber containing air at very low pressure and in which the spark gaps are formed.

With the above mentioned and other objects in view, the invention consists in the construction and novel combination of parts hereinafter described, illustrated in the accompanying drawings, and pointed out in the appended claims; it being understood that various changes in the form, proportion, size, and minor details of construction, within the scope of the claims may be resorted to without departing from the spirit or sacrificing any advantages of the invention.

To more fully comprehend the invention reference is to be had to the accompanying sheet of drawing, disclosing a single spark discharge and in which—

Figure 1 is a longitudinal central sectional view of my improved device, disclosing the electrodes and the manner of adjusting the same, the chamber in which the same are mounted, and the receptacle for containing the cooling fluid. Fig. 2 is a transverse sectional view taken on line $x-x$ —Fig. 1.

Referring more particularly to the drawings wherein is disclosed one pair of spark

gaps of one or more gaps in series, the reference numeral 1 designates suitable end plates of non-conducting material, and the same are maintained in spaced relation by 60 a circular shell 2, preferably of non-conducting transparent material and provided in its surface with threaded openings 3 and 4, and the end edges of said shell engage suitable packing 5 seated in grooves 6 formed on the corresponding inner faces of the end plates.

An interior stationary electrode 7 in the form of conical chambers 8 and 9 connected adjacent their apex in the form of 70 an hour glass is positioned between the end plates and interiorly of the shell 2, and the edges of the shell engage suitable packing 5 seated in grooves 6 formed in the corresponding inner faces of the end 75 members.

Suitable bolts 10 serve to draw the end plates together, and force the edges of the shells 2 and 7 against the packing in the grooves 6 and 6' and maintain fluid tight 80 joints between the same, and when the structure is assembled the air is maintained in the chamber at a very low pressure.

From the above description it will be observed that between the shell 2 and stationary electrode 7 is formed a chamber 11 adapted to receive a suitable cooling fluid such as water and the same may be circulated therethrough through the openings 3 and 4.

Positioned within each of the chambers 8 and 9 in the stationary electrode is a conical electrode 12, of any suitable conducting material, and of a size preferably smaller than the chamber, so as to permit the sparking surface 13 of the electrode to be adjusted 90 relative to the inner sparking surface 14 of the chamber.

Threaded into the base of each electrode is a line terminal rod 15 which extends 100 through and projects beyond the end of a guide sleeve 16 secured to the end plate 1, and provided at the end of each guide sleeve 16 and surrounding the rod projected therethrough is a packing 17 retained in compressed condition by an annular flange 18 carried by a thumb-nut 19 threaded over the end of the guide sleeve, the packing preventing the entrance of air into the chambers.

An adjusting thumb-nut 20 is positioned over the threaded end 21 of each line ter-

2
minal rod and is provided with an annular groove 22 in which is seated the curved end 23 of a member 24 secured to the exterior of the guide sleeve. The curved end 23 is provided with an indicating pointer 24' adapted to lie in coöperative relation with suitable graduations 25 formed on the peripheral edge of the nut 20 and it will be observed that upon the rotation of the nuts 20, the 10 sparking surfaces of the electrodes will be adjusted relative to the sparking surfaces of the chamber.

A slot 26 is provided in the end of each line terminal rod and is adapted to receive 15 an instrument for rotating the rod and electrode when the sparking surfaces become worn and it is required to readjust the electrode independently of the adjusting nut.

It will be apparent from the above description that the sparking surfaces are at 20 all times maintained cool and that the sparking surfaces are adjustable relative to each other so that the most efficient spark gap may be maintained at all times. By providing 25 the conical chambers and the conical electrodes a large area of sparking surface is provided and when the apparatus is in operation sparks are discharged from the surface of one electrode to the surface of the 30 chamber, and from the surface of the other chamber to its corresponding electrode and the result obtained therefrom is more efficient than in devices heretofore provided, and by cooling the sparking surface of the 35 electrodes the sparks in jumping from one surface to the other will be prevented from forming an arc.

Having thus described my invention what I claim as new and desire to protect by Letters Patent is:—

1. In an apparatus of the class described, the combination with a stationary electrode provided with opposed conical chambers therein, an end plate positioned over the 45 outer open end of each of said chambers, a shell surrounding said stationary electrode in spaced relation thereto, and maintained in position by said end plate, said shell providing a fluid receiving cooling chamber sur-

rounding said electrode, a conical electrode 50 positioned within each of said chambers, a terminal rod extending from each of said conical electrodes and projecting through said end plates, and means for adjusting said electrodes relative to said chambers. 55

2. In an apparatus of the class described, the combination with a stationary electrode provided with communicating opposed conical chambers therein, a conical electrode positioned within each of said chambers, a 60 shell surrounding said stationary electrode and providing a cooling chamber, and means for adjusting said electrodes in said chambers.

3. In an apparatus of the class described, 65 the combination with a stationary electrode provided with communicating opposed conical chambers, a shell surrounding said electrode in spaced relation thereto for containing a cooling fluid, end plates for positioning over the outer ends of said conical chambers and the peripheral edges of said shell, a tubular guide sleeve extended outwardly from each of said end plates, a conical electrode positioned within each of said chambers and provided with a terminal rod extended through said end plate and guide sleeve, and means carried by said guide sleeve and coöperating with said terminal rod for adjusting said electrodes in said 70 chambers. 75

4. In an apparatus of the class described, the combination with a stationary electrode provided with opposed conical chambers therein, a conical electrode positioned within each of said chambers, means for adjusting said electrodes in said chamber, and a receptacle surrounding said stationary electrode and adapted to contain a cooling fluid for conveying the generated heat therefrom. 80 85

In testimony whereof I have signed my name to this specification in the presence of two subscribing witnesses.

JOHN LOEFFLER.
